J. W. BOOTH

LIQUID FUEL BURNER VALVE

Filed Sept. 24, 1925

UNITED STATES PATENT OFFICE.

JAMES W. BOOTH, OF BARNSDALL, OKLAHOMA.

LIQUID-FUEL-BURNER VALVE.

Application filed September 24, 1925. Serial No. 53,459.

This invention relates to valves for liquid fuel burners and more particularly to a valve for employment in connection with a burner employed where fuel oil containing 5 foreign matter, as for example, acid sludge, is to be consumed. While such fuels are economical to use, so far as the cost thereof is concerned, nevertheless, they are very difficult to burn because of coking in the 10 burner valves which interrupts the operation of the burners. It is the practice to mix with fuel oils of this low grade, a certain percentage of a lighter oil and agitate the mixture to keep the sludge or other foreign 15 matter in suspension so that such matter will not precipitate. The addition of the lighter oil, however, is an item of expense and does not entirely eliminate the coking of the fuel. The present invention 20 therefore, has as its primary object to provide a valve for such a burner so constructed and operating automatically in such a manner as to entirely prevent coking of the fuel and provide for its delivery to the 25 burner in a condition suitable for substantially perfect combustion.

As stated above, it is customary to keep such fuel in circulation and heretofore mechanical devices, operated exterior to the 30 valve, have been employed for this purpose. The present invention has, as another important object, to provide a valve so constructed that in its operation, coking of the fuel and precipitation of the suspended 35 sludge or other foreign matter will be prevented, and to provide for operation of this valve through the flow of the fuel through the fuel supply pipe, from which it is delivered, by way of the valve, to the burner, 40 thereby obviating the employment of any mechanically operated devices for effecting operation of the valve.

Another object of the invention is to so construct the valve that its component parts 45 may be readily separated or disassembled and the valve cleaned whenever occasion requires.

In the accompanying drawings:

Figure 1 is a vertical longitudinal sectional view through the valve embodying 50 the invention.

Figure 2 is a vertical sectional view taken substantially on the line 2-2 of Figure 1, looking in the direction indicated by the 55 arrows.

Figure 3 is a view in side elevation of the valve stem actuating cam of the valve.

Figure 4 is a perspective view of the member which coacts with the cam shown in Figure 3.

The casing of the valve comprises two sections, one indicated in general by the numeral 1 and the other in general by the numeral 2. The section 1 comprises a tubular body 3 threaded at its opposite ends 65 as at 4, to adapt it to be interposed in the fuel supply line (not shown) and this body is formed in its upper side with an opening indicated by the numeral 5, extending longitudinally of its intermediate 70 portion, and is further provided, exteriorly, at opposite sides of the opening, with outstanding longitudinal flanges 6, the upper sides of which occupy a common plane. The casing section 2 comprises a substantially cylindrical hollow body which is relatively narrow and has an open bottom and is provided exteriorly with an outstanding flange 7 matching the flanges 6 of the casing section 1, bolts 8 being secured through 75 the flanges so as to separably connect the two sections of the casing and thus support the section 2 in upright position upon the section 1. The section 2 of the casing is, as stated, of narrow cylindrical form and comprises a circumferential wall 9 and spaced side walls 10 and 11. The wall 10 of the section 2 is formed or provided with a laterally extending short tubular boss 12 which is interiorly threaded as indicated by the 80 numeral 13, and into this boss there is fitted one end of a cap member or bonnet 14 which is formed with a bore 15 having square threads 16 for a portion of its length and having applied to its outer end a packing 85 nut 17 which provides a fluid-tight fit about an adjusting stem 18 which is fitted in the said bore 15. The stem 18 is provided, for a portion of its length with square threads 19 fitting the threads 16, and at its outer 90 end is provided with a hand wheel 20 by means of which it may be rotated.

The wall 11 of the valve casing is provided with a laterally projecting relatively short tubular extension 20 in axial alignment with the extension 12, and a burner nozzle 21 of hollow conical form is threaded onto the said extension 20 and has a fuel orifice 22 at its outer or minor end and which is in axial alignment with the extensions 12 and 20 and 100 105 110

the bore 15 of the cap member 14. A spider 23 is mounted within the extension 20 and securely held in place and is provided centrally with an opening 24 in axial alignment with the orifice 22. The valve body is indicated in general by the numeral 25 and the same comprises a cylindrical body portion 26 which is both rotatably and slidably fitted in the opening 24. This body is tapered at its intermediate portion to a reduced diameter as indicated by the numeral 27, and terminates in an axially extending stem 28, the outer end of which is presented close to the inner end of the orifice 22, as best shown in Figure 1 of the drawings. At a point intermediate its length, the valve body 26 is formed with a circumscribing shoulder 29 and from this shoulder to its other end, is threaded as indicated by the numeral 30. The numeral 31 indicates the hub of a fluid-impact wheel or rotor embodying a plurality of radial blades 32 which extend from the hub 31 and which are of a width somewhat less than the interior width of the casing section 2. The hub 31 is threaded onto the threaded portion of the valve body 26 and abuts against the shoulder 29, and a cam element, indicated in general by the numeral 33 and illustrated in Figure 3 of the drawings, is supported upon the threaded portion of the body 26, the said cam member comprising a cylindrical body portion 34 interiorly threaded as indicated by the numeral 35, to fit the threads of the threaded portion of the valve body 26. The said body portion 34 of the cam member abuts against the hub 31 of the impact wheel and the body is formed exteriorly with a circumferential cam rib 36 which has substantially the form of a closed helix.

The threaded portion of the valve body 26 is formed interiorly with an axially extending bore 37, and at that end of the stem 18 which extends into the valve casing is cylindrical and smooth and fits within the said bore 37 as clearly shown in Figure 1 of the drawings. This portion of the stem is indicated by the numeral 38, and between this portion and the threaded portion 19, the stem is formed with threads 39, and a collar 40 is interiorly threaded and fitted onto this portion of the stem and is provided with a finger 41 located at the periphery and extending parallel with the portion 38 of the stem 18 and in close proximity to the circumferential surface of the cam body 34, the finger having a notch 42 formed in its inner side which is presented toward the said cam body, to accommodate the cam rib 36. It will be observed by reference to Figure 1 of the drawings, that the valve body 26 not only rotatably fits the portion 38 of the adjusting stem 18, but is also slidably longitudinally thereon.

65 The automatic valve embodying the inven-

tion is to be installed in the pipe line which ordinarily leads from the source of liquid fuel supply to the burners and includes a return to the said source and it will be understood that there is, therefore, a constant flow of fuel oil through the tubular body 3 of the casing section 1 of the valve and that inasmuch as the under side of the impact wheel extends into the said body of the casing section 1, rotary motion will be continuously imparted to the said wheel as the liquid fuel flows through the said casing section. As the impact wheel rotates, rotary motion will, of course, be imparted to the valve member 25 and, due to the coaction of the cam rib 36 of the cam member 33 with the finger 41 of the collar 40, reciprocatory motion will likewise be imparted to the said valve member 25 so that the extremity of its portion 28 will be moved backwardly and forwardly toward and from the fuel orifice 22 of the burner nozzle 21, thus agitating the fuel passing through this orifice and preventing the accumulation of sediment or sludge therein, which would interfere with proper functioning of the burner. It will be evident, therefore, that the valve is entirely automatic in its operation and that it operates through the flow of fuel oil through the valve casing section 1. Inasmuch as through rotation of the stem 18, this stem may be adjusted longitudinally, the valve member 25 may be bodily adjusted with relation to the orifice 22 so that the extremity of its portion 28 may be caused to operate at such a distance from the orifice 22 as to insure of the best results, depending upon the physical characteristics of the fuel oil to be consumed.

It will be understood, of course, that by adjusting the stem 18, the flow controlling portion 28 of the valve body 25 will be correspondingly adjusted with relation to the fuel outlet orifice 22, so as to control the flow of fuel through the orifice, it being evident that, notwithstanding the reciprocatory motion imparted to the said valve body, adjustment of the body as a whole toward or from the orifice will respectively decrease or increase the flow of liquid fuel past the flow controlling portion 28 of the valve body and through the orifice.

Having thus described the invention, what I claim is:

1. A fluid fuel burner valve comprising a fuel nozzle having a fuel outlet orifice, a valve element having a flow-controlling portion presented toward the orifice, and means operated through the flow of fuel in the valve for imparting continuous reciprocatory motion to said element toward and from the said orifice.

2. A fluid fuel burner valve comprising a fuel nozzle having a fuel outlet orifice, a valve element having a flow-controlling por-

tion presented toward the orifice, means for imparting continuous reciprocatory motion to said element toward and from the said orifice, and means operable to bodily adjust 5 the said element with relation to the orifice.

3. A fluid fuel burner valve comprising a fuel nozzle having a fuel outlet orifice, a valve element having a flow-controlling portion presented toward the orifice, means for 10 imparting continuous reciprocatory motion to said element toward and from the said orifice and actuated through flow of fuel through the valve, and means operable to bodily adjust the said element toward and 15 from the said orifice.

4. A fluid fuel burner valve comprising a casing having a fuel passage extending therethrough, a fuel nozzle in communication with the casing and having a fuel outlet orifice, a valve element rotatably and 20 slidably supported within the casing and having a flow-controlling portion presented toward the orifice, a rotor within the casing having blades presented in the path of flow 25 of fuel through the casing, and means operating through rotation of the rotor for imparting continuous reciprocatory motion to the valve element toward and from the said orifice.

5. A fluid fuel burner valve comprising a casing having a fuel passage extending therethrough, a fuel nozzle in communication with the casing and having a fuel outlet orifice, a valve element rotatably and 30 slidably supported within the casing and

having a flow-controlling portion presented toward the orifice, a rotor within the casing having blades presented in the path of flow of fuel through the casing, means operating 40 through rotation of the rotor for imparting continuous reciprocatory motion to the valve element toward and from the said orifice, and manually operable means for bodily adjusting the valve element with respect to the said orifice. 45

6. A fluid fuel burner valve comprising a casing having a fuel passage extending therethrough, a fuel nozzle in communication with the casing and laterally disposed with relation thereto and having a fuel 50 outlet orifice, a valve body rotatably and slidably supported within the casing and having a flow-controlling portion presented toward the orifice, the said body having a bore, an adjusting stem having threaded 55 bearing in the casing whereby to effect longitudinal adjustment of the stem upon rotation thereof, the stem having a portion slidably fitting in the bore of the said valve body, a rotor supported upon the valve body 60 and having blades presented in the path of flow of fuel through the casing, a cam element upon the said valve body, and a fixed element upon the said adjusting stem co-acting with the cam element whereby to 65 effect continuous reciprocatory motion of the valve body toward and from the orifice in the rotation of the rotor.

In testimony whereof I affix my signature.
JAMES W. BOOTH. [L. S.]
